UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

ATTACHMENT FOR SEWING-MACHINES.

1,369,406.

Specification of Letters Patent. Patented Feb. 22, 1921.

Application filed May 11, 1918. Serial No. 234,008.

To all whom it may concern:

Be it known that I, ALBERT H. DE VOE, a citizen of the United States, residing at Westfield, in the county of Union and State 5 of New Jersey, have invented certain new and useful Improvements in Attachments for Sewing-Machines, of which the following is a specification, reference being had therein to the accompanying drawings.

10 This invention relates to sewing machines and particularly to attachments therefor.

It aims to provide a new and improved combination and arrangement of attachments for making an ornamental facing for 15 body garments of the character shown in my prior Patent No. 1,239,675, granted September 11, 1917, on a combined ruffling and ornamental stitching machine. The exacting demands of the trade necessitate precision and uniformity in production and the 20 present invention answers these requirements.

The invention comprises a strip-folder, supported from beneath the cloth-plate of a 25 sewing machine and inclined upwardly toward its delivery end which is located in front of the feed-dogs, a lace-guide, supported by the strip-folder and between the same and the cloth-plate, a pivoted lace- 30 conductor, leading a strip of lace or edging to the line of feed at substantially right angles and then reversing it into parallelism with the line of feed before the lace or edging enters the lace-guide, and a stripping 35 plate, having an upright edge guiding wall for directing a knit body-fabric into abutting relation with the lace or edging, all of the above mentioned features being located in advance of a combined ruffling and ornamental stitching machine for concealing the 40 abutting edges of the knit body fabric and lace with a covering-thread of an attractive color in a figure 8 pattern and for simultaneously stitching both the fabric and lace 45 to a reinforcing facing strip whose raw edges are infolded. The knit body fabric is differentially fed to the stitching point by the ruffling blade to make the stitched article smooth and flat and to prevent it from 50 being drawn or puckered.

An embodiment of the invention is illustrated in the accompanying drawings in which Figure 1 is a plan view of the invention applied to a machine, parts below the 55 cloth-plate being exposed by fracturing the

latter. Fig. 2 is a front elevation of the attachment with the cloth-plate appearing in section. Fig. 3 is a side elevation of the same with the cloth-plate appearing in section. Fig. 4 is a side elevation of the stitch-forming and ruffling instrumentalities above the cloth-plate; Fig. 5 is a cross-section of the work done with this attachment, and Fig. 6 is a perspective view of the bracket for supporting the lace-conductor.

The invention is shown applied to a combined ruffling and ornamental stitching machine having a ruffling blade 1 secured to an attachment arm 2 supported in a bearing of a pivoted hanger 4 and rocked through 60 a lever-arm 5 in a manner fully disclosed in my pending application Serial No. 132,521, filed November 21, 1916, and also having a looping finger 9 mounted and operated substantially as disclosed in my pending application Serial No. 147,295, filed February 8, 1917, the looping finger in its movement laying an ornamental thread in a figure 8 pattern about each of the pair of needles 10 spaced from which, for a purpose 65 appearing later, is a third needle 11. The work is fed by the feed-dogs 12 and the cooperating presser-foot 13 through holes in which the needles pass in a manner well known.

In advance of the presser-foot and stitch-forming mechanism, the cloth-plate 14 is provided with a removable section 15 cut away to form an opening 16, one side of which appears in Fig. 4. A stripping plate 17 having an 70 edge-guiding wall 18, is adjustably secured over the opening 16. A shank 19 extending laterally from the stripping plate is slotted at 20 and secured by a clamp-screw 21 to an arm 22 which is pivoted by screws 23 to the 75 removable section 15 of the cloth-plate from which rises a stop-pin 23' for locating the working position of the stripping plate.

The above mentioned construction is all located above the cloth-plate, what follows 80 is largely below.

With its upper surface substantially flush with the cloth-plate is a lace-guide 24 having an edge-guiding wall 25, an overhanging lip 26 and a depending and lateral supporting flange which is slotted at 27 for the screws 28 adjustably securing the guide to a plate 29 projecting from one side of a strip-folder 30 to which it is soldered or otherwise suitably secured. The strip-folder 30 85

has the usual edge-folding scrolls or channels 31 and its rectangular base-plate 32 is movably mounted in a dove-tailed slideway 33 provided in a supporting plate 34 screwed 5 to a rod 36 which is adjustably clamped by the screws 37 in a lug 38 depending from the cloth-plate 14. The strip-folder 30 is inclined upwardly from its receiving to its delivery end which is located substantially 10 in a plane with and slightly behind the delivery end of the lace-guide 24 which, it will be remembered, is flush or nearly so with the cloth-plate. A spring 39 sunk in the supporting plate 34 below the slideway 33 frictionally retains the strip-folder and lace-guide in working position which position is determined by the stop-pin 40 depending from the base-plate 32 to which the strip folder is fixedly secured. 15 20 A Z bracket 41, having an lateral arm 42 in which is threaded a stud-screw 43, pivotally supports a lace-conductor 44 and a spring-catch 45 beneath the arm 42 retains the lace-conductor in normal working position 25 underneath the cloth-plate during the operation of the machine while a friction washer 46 at all times steadies the conductor 44 against too free movement. The lace-conductor 44 extends preferably at right 30 angles or substantially so to the line of feed and its free end 47 is bent upwardly and over at an angle into approximately parallelism with the line of feed. Mounted on the lace conductor 44 at its receiving end is a 35 guide-eye 48, intermediate its ends is an adjustable tension device 49 of the plural rod type, and at its free end 47 is an adjustable closed guide-loop 50. In the bent reversing wall 51 of the lace-conductor is provided an opening 52 for confining the lace during its 40 reversal and through a slot 53 communicating therewith the lace may be readily introduced. 45 With a combined ruffling and stitching machine the above described combination and arrangement of devices may be used to produce an ornamentally edged knit garment whose front is shown in section in Fig. 5. The knit body garment indicated 50 at 54 is guided by the wall 18 of the stripping plate into abutting relation and in a plane with the lace or edging 55, the line of abutment being located between the seams 56 made with the needles 10 around which 55 needles covering-thread 57, of a suitable pleasing color, preferably in a figure 8 pattern, is laid to conceal the abutting edges from view as well as lend an attractive appearance to the product. Preferably a facing strip 58, of woven or other suitable material, is secured to the work with one side 60 underlying the meeting edges of the body-garment and lace and with its other side secured by the seam 59 of the needle 11 to 65 the knit body fabric. The raw edge of the

knit body fabric is thus secured against raveling without folding it into a bulky ridge, the meeting edges of the fabric and lace are also effectively concealed from view, and the lace and facing strip may be led to the work without requiring attention from the operator during the operation of the machine. 70

Having thus set forth the nature of the invention, what I claim herein is— 75

1. In a sewing machine having stitch-forming mechanism including a pair of needles and a looping finger for laying a covering-thread around two of the needles and having also ruffling mechanism including a blade, in combination, a stripping plate coöoperating with the blade and having an edge-guiding wall for an elastic body-fabric, a lace-guide, said edge-guiding wall and lace-guides being arranged to direct the edges of the fabric and lace into abutting relation with their line of abutment between the pair of needles. 80

2. In a sewing machine having stitch-forming mechanism including a plurality of needles two of which are close together, and coöperate with a looping finger and having also a ruffling mechanism including a ruffling blade, in combination, a stripping plate coöoperating with the ruffling blade and having an edge-guiding wall for a body-fabric, a lace-guide, said edge-guiding wall and lace-guide being arranged to direct the body-fabric and lace to the two close needles, and a strip-folder for directing a facing 95 strip to the stitch-forming mechanism. 100

3. In a sewing machine, in combination, a strip-folder, an edge-guide and a lace-guide intermediate said strip-folder and edge-guide for directing a piece of lace into 105 abutting relation with a body-fabric whose edge is controlled by said edge-guide, said strip-guide directing the strip across the line of contact between the body-fabric and the lace, the controlling faces of said edge 110 and lace guides being substantially in a vertical plane parallel with the line of seam formation and the controlling faces of said strip-guide being on opposite sides of said vertical plane. 115

4. In a sewing machine having a work-support, in combination, a strip-folder below the work-support, an edge-guide above the work-support, and a lace-guide between the strip-folder and the work-support. 120

5. In a sewing machine having a work-support, a strip-folder, supported from beneath the work-support, an edge-guide, and a lace-guide between said strip-folder and work-support and a lace-conductor for leading the lace in an angular path beneath the work-support. 125

6. In a sewing machine having a work-support, in combination, a strip-folder, an edge-guide, a lace-guide, a lace-conductor, 130

and a lace tensioning device fixed in position adjacent said lace-conductor.

7. In a sewing machine having a work-support, in combination, stitch-forming mechanism including a plurality of needles and a looping finger coöperating with said needles, work-feeding mechanism, and means for directing a body fabric and lace edging into abutting relation in a common plane with their line of contact between the needles with which the looping finger coöperates, said means including guides supported from opposite sides of the work-support one of which is shaped to direct the lace in a path below the work-support and at a substantial angle to the line of seam formation.

8. In a sewing machine, in combination, stitch-forming mechanism including a plurality of needles and a looping finger coöperating with said needles, work-feeding mechanism, means for directing a body fabric and lace edging into abutting relation in a common plane with their line of contact between the needles with which the stitch-finger coöperates, and means for directing a facing strip to the stitch-forming mechanism with one side thereof lapping the abutting edges of the body fabric and lace.
9. In a sewing machine, in combination, stitch-forming mechanism including a plurality of needles and a looping finger coöperating with said needles, work-feeding mechanism, a work-support, an edge-guide and a lace-guide arranged on opposite sides of the work-support, and means permitting adjustment of said guides to bring the work

edges controlled thereby into abutting relation between two of the needles with which said looping finger coöperates.

10. In a sewing machine having stitch-forming mechanism including a pair of needles for making an ornamental seam, in combination, a lace-guide for directing an edge of a strip of lace between the pair of needles, means for leading the lace beneath the work-support in an angular path to the lace-guide, said means being pivotally supported for movement from beneath the work support for convenience in introducing lace.

11. In a sewing machine having stitch-forming mechanism including a pair of needles for making an ornamental seam, in combination, a lace-guide for directing an edge of a strip of lace between the pair of needles, means for leading the lace beneath the work-support in an angular path to the lace-guide, said means including a turning wall for reversing the lace before it reaches the lace-guide.

12. In a sewing machine having stitch-forming mechanism and work-feeding mechanism and a work-support, in combination, a strip-guide located beneath the work-support, a lace-guide supported by said strip-guide, an edge-guide, a section of said work-support being removable and supporting said edge-guide, whereby access may be had to the lace-guide for convenience in introducing the work.

In testimony whereof, I have signed my name to this specification.

ALBERT H. DE VOE.
